UNITED STATES PATENT OFFICE.

THOMAS C. FORBES, OF LOS ANGELES, CALIFORNIA, ASSIGNOR TO LOS ANGELES ROTARY GAS ENGINE COMPANY, OF LOS ANGELES, CALIFORNIA, A CORPORATION OF CALIFORNIA.

MUFFLER.

960,530.

Specification of Letters Patent. Patented June 7, 1910.

Application filed July 21, 1909. Serial No. 508,855.

To all whom it may concern:

Be it known that I, THOMAS C. FORBES, a citizen of the United States, residing at Los Angeles, in the county of Los Angeles and 5 State of California, have invented a new and useful Muffler, of which the following is a specification.

This invention relates to a muffler adapted for internal combustion engines of the rotary type in which the cylinders bodily revolve and the main objects of the invention are to reduce the noise of exhaust as much 10 as possible and prevent back pressure in the cylinders.

15 Referring to the drawings: Figure 1 is a side elevation of an engine equipped with the muffler, part of the muffler being in section. Fig. 2 is an enlarged cross section on line x^2-x^2 of Fig. 1. Fig. 3 is an enlarged 20 cross section on line x^3-x^3 of Fig. 1.

The engine shown has five cylinders 1, which are mounted to rotate around a shaft 2.

3 Designates the muffler, which comprises 25 an annular chamber consisting of an outer channel member 4, and an inner channel member 5, the flanges 6 of which fit within the member 4 and are secured by screws 7. The muffler may be secured to the cylinders 30 in any desired manner, as for example, by bolts 8 which pass through lugs 9 cast on the cylinders.

A series of partitions 10 divide the interior of the muffler into a series of chambers 35 11, while a transverse partition 12 forms an inner chamber 13, and an outer chamber 14. Each cylinder has exhaust passages 15 which open into the inner chamber 13 and the discharge end portions of the passages 40 form an acute angle with the muffler so as to approximate the plane of movement of the muffler, and they discharge in a direction opposite to the direction of movement of the muffler. The cylinders and muffler rotate in the direction indicated by the arrow 45 in Fig. 2 and as the tendency of the exhaust gas discharged into the muffler is to lag behind the speed of the muffler a certain amount of suction is produced acting outwardly through the exhaust ports which facilitates the discharge of the exhaust gas 50 therefrom.

The gas is discharged into the chamber nearly parallel with the chamber producing

a rotary motion of the gas past the port of 55 the succeeding cylinder, thereby producing a suction effect in the succeeding cylinder, and preventing back flow of the gas thereinto, thus obviating contamination of the incoming charge in that cylinder. 60

The exhaust gas passes from the inner chamber 13 through ports 15' in the partition 12 into the chamber 14, the perforations 15' being numerous and distributed along the entire partition 12, so that the gas 65 is split up and uniformly distributed. From the chamber 14 the gas passes through perforations 16 in the innermost partition 10, and thence through similar perforations in the succeeding partitions 10 traversing the 70 several chambers 11. The perforations 16 of alternate partitions 10 are located near their larger diameter, while those of the intervening partitions are located near the inner diameter, thus causing the gas to weave 75 back and forth making a long circuit before it is discharged from the muffler. From the outer chamber 11, the gas issues to the atmosphere through a series of perforations 17. The bridge 18 which is formed between 80 the passages 15 prevents the piston from striking the edge of the ports 15 which would result if a single large port were employed.

The partitions 10 are spaced apart by 85 rings 18, while the outermost partition 10 is spaced from the outer wall 5 by the flanges 6 thereof.

What I claim is:

1. A muffler for rotary engines comprising a continuous annular chamber rotating with the engine and having a communication with the exhaust port of the cylinder, and having a discharge opening. 90

2. A muffler for rotary engines comprising an annular chamber rotating with the engine and having a series of openings in communication with the respective exhaust ports of the cylinders, and having a series 95 of discharge openings.

3. A muffler for rotary engines comprising a continuous annular chamber rotating with the engine, means for discharging exhaust gas from a cylinder into the annular chamber in a direction opposed to the direction of rotation of the chamber, the chamber having a series of discharge openings. 100 105

4. A muffler for rotary engines comprising

ing an annular chamber rotating with the engine, the wall between the annular chamber and a cylinder being provided with a curved passage for discharging the exhaust 5 gas into the annular chamber in a direction opposed to the direction of rotation of the chamber, the chamber having a series of discharge openings.

5. A muffler for rotary engines comprising an annular chamber rotating with the engine, the wall between the annular chamber and a cylinder being provided with a pair of curved passages for discharging the exhaust gas into the annular chamber in a 10 direction opposed to the direction of rotation of the chamber, the chamber having a series of discharge openings.

6. A muffler for rotary engines comprising an annular chamber rotating with the engine and having communication with the exhaust port of a cylinder, a series of partitions in the annular chamber, the partitions having ports, and the chamber having a series of discharge openings.

25 7. A muffler for rotary engines comprising an annular chamber rotating with the engine and having communication with the exhaust port of a cylinder, a series of radial partitions in the chamber, alternate partitions having ports near their outer circumference, intervening partitions having ports 30 near their inner circumference, the

outermost chamber formed by the partitions having a series of discharge openings.

8. A muffler for rotary engines comprising an annular chamber rotating with the engine and having communication with the exhaust port of a cylinder, a series of radial partitions in the chamber, alternate partitions having ports near their outer circumference, intervening partitions having ports near their inner circumference, the outermost chamber formed by the partitions having a series of discharge openings, and a circular partition at right angles to the radial 40 partitions and having a series of ports.

9. A muffler for rotary engines comprising an annular chamber consisting of an inner channel member, and an outer member with flanges overlapping the inner member, a series of radial partitions in the chamber, rings spacing the partitions apart, the partitions having ports, the inner member being in communication with the exhaust port of a cylinder, the outermost chamber 45 having discharge openings.

In testimony whereof, I have hereunto set my hand at Los Angeles, California, this 28th day of June 1909.

THOMAS C. FORBES.
